TUNNEL LINER

Charles T. Whitescarver, Chicago, Ill., assignor to
Anthony C. Fischer, Chicago, Ill.

Application January 18, 1935, Serial No. 2,353

8 Claims. (Cl. 61—45)

The invention relates to sheathing for tunnels or sewers which are driven through soft or loose earth where considerable exterior pressure is exerted by the soil and the sheathing is required as the excavation proceeds in advance of the usual concrete structure.

One object of the invention is to provide sheathing which comprises segments formed of plates of metal and reinforcing bars which are adapted to be secured to ribs placed between the series of segments and by which a substantial saving in weight and cost of the segments may be effected.

Heretofore it has been customary in tunnel liners to form integral flanges on the segments of heavy plate metal and another object of the invention is to provide an improved segment which is light in weight and which comprises plates which can be cut from continuous sheets and have attached thereto reinforcing bars with means for securing them to contiguous ribs to dispense with flanges on the plates.

Another object of the invention is to provide a sheathing in which the segments of each successive series are secured to intermediate ribs independently of the contiguous series so that after one series of segments has been secured in place between ribs, the next succeeding series of segments can be secured to the last rib installed without disconnecting the bolts used in securing the previously installed series, to effect a saving in the labor and cost of installation.

Another object of the invention is to provide an improved segment for sheathing for this purpose which is adapted efficiently to carry its required load and can be produced at a low cost.

Other objects of the invention will be apparent from a consideration of the following detailed description.

The invention consists in the several novel features hereinafter set forth and more particularly defined by claims at the conclusion hereof.

In the drawings:

Fig. 1 is a section of a tunnel or sewer embodying the invention. Figs. 2, 3, and 4 are perspectives of different forms of segments used in each row. Fig. 5 is a vertical section showing the overlapping plates of adjacent segments. Fig. 6 is a longitudinal section on line 6—6 of Fig. 1. Figs. 7 and 8 are perspectives illustrating the manner of forming on the reinforcing bars of the segments ends whereby they can be bolted to the transverse ribs. Fig. 9 is a section through one of the joints between the sections of one of the transverse ribs. Fig. 10 is a sectional developed

plan showing the staggered adjacent rows of segments. Fig. 11 is a similar view of a modified form of the invention. Fig. 12 is a section on line 12—12 of Fig. 11.

The invention is exemplified in a sheathing comprising a series of transverse ribs 15 or beams, usually conforming to the contour of the excavation at the sides of and above the base. These ribs are spaced apart longitudinally of the tunnels and are built up of sections of I-beams 10 having a web 15^a and flanges 15^b. The sections have abutting ends and are secured together by splice-plates 16 and bolts 17 which extend through said plates and the web 15^a of the adjacent ends of rib sections. The plates 16 are outwardly bulged or convex and their ends are seated in the angles between the web and flanges of the rib, so that when the bolts 17 are tightened the plates will rigidly and effectively secure the sections of the ribs together. The lowermost section 20 of each rib 15 is set between and bolted to a shoe 32 on a suitable base beam 33. By constructing the ribs of sections thus secured together, they can be easily handled and transported.

The sheathing also comprises a row of segments 18 between each adjacent pair of ribs 15 to form a substantially continuous sheathing throughout the length of the tunnel or sewer. Each segment 18 comprises a metal plate 19 having corrugations 19^a extending longitudinally of the segment 30 and transversely of the tunnel from end to end of the plate and one or more bars 20 for reinforcing the plates and adapted at their ends to be bolted to the webs 15^a of the ribs 15. Each bar 20 is angular in cross section and comprises a 35 circumferential flange 23, a radial flange 24 and integral ends 21 which are provided with bolt holes 22. Each side margin of each corrugated plate 19 has welded thereto a marginal reinforcing wire 26. The inner crowns of each of the 40 corrugated plates 19 where they contact with the flange 23 are spot-welded to the outer faces of flanges 23 of bars 20. Bolts 25 extend through the holes 22 in the ends 21 of bars 20 and the web 15^a of the contiguous rib to secure the segments to the ribs. In fabricating each bar 20 a V-shaped notch 28 is cut in each end portion of the radial flange 24, as illustrated in Fig. 7. The end portion 23^a of the flange 23 is then bent on a line at the apex of the notch 28 until the edges 50 of the flange 24 at the notch abut and the portion 23^a of flange 23 is at right angles to the remainder of said flange 23 and forms the integral end 21 extending at right angles to the flanges 23 and 24. The abutting edges at the notch are 55

spot-welded together as at 29. This exemplifies a simple and economical manner of forming the angle bars of the segments with integral ends for abutting the webs 15^a and attachment to the 5 ribs 15. The angle bars 20 are adapted to enter the space between the flanges of the ribs 15 and the sides of the plates 19 terminate inwardly of the ends of these bars, and under the outer flanges 15^b of the ribs. The segments in each 10 row at the top of the tunnel have attached thereto one bar 20 located centrally between its ends, as shown in Fig. 4. The next segments in each row are provided with a bar 20 at one end thereof and a central bar 20, as illustrated in Fig. 3. The 15 next segments of each row have attached thereto a central bar 20 and a bar at each end, as illustrated in Fig. 2. In installing each row of segments the topmost segment with the central reinforcing bars 20 is first bolted to the webs 20 of adjacent ribs 15. Next, the necessary number of segments with a reinforcing bar at one end and a central reinforcing bar are installed between the ribs 15, the successive segments being placed so that their upper ends which have 25 a bar will underlie the marginal portion of the plate 19 on the next preceding bar at which no bar is provided, as illustrated in Fig. 5. The ends of the segments at the top of the arch which are provided with only a central bar 20 will overlap the end portions of the adjacent segments at both sides of the center of the tunnel, so that the end portions of the top segment will be supported by the end bars on the underlying ends of the 30 segments. The lower ends of the segments with two bars will overlap the adjacent segments so as to be supported thereby. By this construction the segments make it possible to use the minimum number of bars necessary to adapt the segments to carry the imposed load. The segments 35 of alternate rows between the ribs are staggered as illustrated in Fig. 10 and the ribs are provided with holes for bolts for securing the bars 20 of the segments of two adjacent rows. As a result 40 bolts 25 for securing the bars of one row of segments will pass through the ends 21 of said bars of one row and the web of the rib independently 45 of the bars of the next row of segments because the bars of one row of segments will be disposed circumferentially intermediate the bars of adjacent rows. By reason of this construction and arrangement and dispensing with flanges on the 50 plates, each row of segments can be secured by bolts to both of the ribs last set up without removing the bolts from the installed row when 55 the bars of the next row of segments are installed.

In the construction of a tunnel or sewer through soft or loose earth, the excavation is made substantially of the cross section necessary 60 for the installation of the sheathing and of sufficient depth for the installation of two ribs 15 and one row of segments. Sections of the ribs for two longitudinally spaced ribs 15 are set up on the shoes 32 and secured together by the splice- 65 plates 16 and bolts 17 to form complete ribs. The topmost segment is then secured to both ribs by bolts 25 which pass through holes 22 in the ends of its bar 20 and the webs of the ribs abutting against the ends of the bar. Next, the 70 proper segments with bars 20 at one end and a central bar 20 are similarly secured to the ribs with their upper margins underlapping the ends of the top segment. Next, two-bar segments are continued to the points where their lower ends 75 will overlap the three-bar segments at the sides

of the tunnel. A complete sheathing will thus be formed for the excavated sections of the tunnel. Next, the excavation will be advanced until there is space for another row of segments. The next rib will then be installed and the segments in staggered relation to the preceding row will be secured at both sides to the ribs as previously described. This procedure can be continued throughout the construction of the length of the tunnel, the segments of alternate rows 10 being staggered as described so that every other row will be composed of plates similarly disposed. After the sheathing has been installed, a concrete wall 30 is built into the sheathing, as well understood in the art. 15

In the modification illustrated in Figs. 11 and 12 the sheathing comprises rows of segments each of which is formed of two sections 34 and 35. Each of said segments comprises a reinforcing bar composed of sections 36 and 37 welded to the 20 plates of the sections respectively and provided with integral ends 38 by which they can be bolted to adjacent ribs. A connecting plate 39 is riveted as at 40 to the radial web of each of the sections 37 of the bar and is secured by bolts 41 to the 25 other section 36 of the bar. In installing these segments one row of sections may be secured to one of the ribs and acting in cantilever will support the earth beyond the rib until the next rib is installed and the mating row of segment 30 sections is installed and the plates are secured by bolts 41 to secure the sections of the bars together.

The invention exemplifies a tunnel sheathing comprising segments which are light in weight, 35 comprise structurally formed bars united to the plates, and can be easily secured to the ribs independently of the succeeding rows of segments. The invention also exemplifies segments which can be produced at a low cost and installed at a 40 low cost.

An important advantage of the invention is that after a segment has once been installed and connected to the furthermost rib set up in the excavation, it is not necessary to detach it in 45 connection with the installation of the next row of segments.

Another advantage is that the plates are continuously corrugated from end to end to render them rigid and can be cut from continuous sheets 50 of metal, thus making it possible to produce the segments at a low cost.

The invention is not to be understood as restricted to the details set forth, since these may be modified within the scope of the appended 55 claims, without departing from the spirit and scope of the invention.

Having thus described the invention, what I claim as new and desire to secure by Letters Patent is:

1. A tunnel liner segment comprising a plate and a transverse thrust bar united to the plate, extending across the plate, and provided with means at its ends whereby it may be bolted to contiguous ribs. 65

2. A tunnel liner segment comprising a plate and a transverse angle bar provided with circumferential and radial flanges, extending across and secured to the plate, and having the end portions thereof bent inwardly at right angles to the 70 flanges to form integral means whereby it may be secured to contiguous ribs.

3. A tunnel liner segment comprising a plate of metal corrugated circumferentially from end to end thereof, and a transversely extending thrust 75

bar united to said plate, and having the ends thereof bent inwardly at right angles and provided with holes for bolts whereby said bar may be secured to contiguous ribs.

5 4. A tunnel liner segment comprising a plate corrugated circumferentially from end to end thereof, and a transversely extending angle bar having a flange welded to said plate and provided with integral means at its ends whereby it 10 may be secured to contiguous ribs.

5 5. A sheathing for a tunnel or the like comprising a row of segments, each segment comprising a plate and one or more transverse thrust bars united to the plate, means for securing the 15 ends of the bars to ribs, some of the plates having margins lapping the ends of contiguous segments.

20 6. A sheathing for a tunnel or the like comprising a pair of laterally spaced ribs, a row of segments fitting between the ribs, each comprising a plate and one or more transverse bars united to the plate and provided with integral

ends extending at right angles thereto, and means for securing the ends of the bars to the ribs.

7. A sheathing for a tunnel or the like comprising transverse ribs, rows of segments fitting 5 between the ribs, each comprising a plate and one or more transverse thrust bars united to the plate and provided with ends, and means extending through said ends and the ribs for securing the segment to the ribs, the bars of the segments of 10 one row being secured to the ribs independently of the segments of adjoining rows.

8. A tunnel liner segment composed of sections, each section comprising a plate section and a transversely extending bar section, the bar 15 sections being united to the plate sections and provided with integral means at their ends whereby they may be secured to contiguous ribs, and means for securing contiguous bar sections together to secure the sections together when in- 20 stalled.

CHARLES T. WHITESCARVER.
